UNITED STATES PATENT OFFICE.

JACOB C. LARSEN, OF COLUMBUS, OHIO, ASSIGNOR TO THE BUCKEYE STEEL CASTINGS COMPANY, OF COLUMBUS, OHIO.

BOLSTER CONSTRUCTION FOR SIX-WHEEL TRUCKS.

1,380,569.

Specification of Letters Patent.

Patented June 7, 1921.

Application filed January 17, 1921. Serial No. 437,857.

To all whom it may concern:

Be it known that I, JACOB C. LARSEN, a subject of the King of Denmark, and a resident of Columbus, in the county of Franklin and State of Ohio, have invented certain new and useful Improvements in Bolster Construction for Six-Wheel Trucks; and I do hereby declare the following to be a full, clear, and exact description of the invention, such as will enable others skilled in the art to which it appertains to make and use the same.

My invention relates to an improvement in bolster construction for six wheel trucks, and is designed particularly as an improvement on Patent No. 1,253,842 granted to G. T. Johnson and myself January 15th, 1918, the object being to simplify the construction; to save weight and also provide more space at one end of the truck which can be utilized advantageously in providing more room for draft gear and draft gear devices.

A further object is to provide a bolster system which will transmit both the side and center bearing loads properly to the truck frame and also which will permit of the comparatively easy removal and replacement of the center axle and its wheels.

With these and other objects in view, my invention consists in the details of construction as will be more fully explained and pointed out in the claims.

In the accompanying drawings Figure 1 is a view in plan of my improvement; Fig. 2 is a view in side elevation thereof; Fig. 3 is a view in section on the line A—B, of Fig. 1 and Fig. 4 is a section on the line C—D, of Fig. 1.

The invention is applicable for use with any six wheel truck, and while I have illustrated one form of side frame in connection with my improvement I have done so for the purpose of illustration only, and not with the intention of limiting my invention to such, or any other particular construction of side frame.

7 represents the truck side frames, there being two to each side with their adjacent ends overlapping, as shown in Fig. 1 for the connection therewith of the frames 8 carrying the bearing for the center axle 9. Each side frame 7 has a bearing for a journal of an end axle 10, and each is also provided with an opening 11 for the reception of one end of a transverse or auxiliary bolster, each

bolster being yieldingly supported adjacent its ends, on springs 13 seated within said openings 11. The transverse bolsters are located as shown, one between the front and middle axles, and the other between rear 60 and middle axles.

Transverse bolster 12 is mounted at its ends on springs 13 carried by the side frames 7 in a vertical plane between the center axle and one end axle and is provided with two integral parallel longitudinal bolsters 14 the free ends of which are hook shape as at 15 to engage and rest on the top surface of the transverse bolster 12^a, which latter is in a vertical plane between the center axle 70 9 and one of the end axles 10. The hook shaped ends of the longitudinal bolsters 14 are constructed to make a close fit with bolster 12^a so as to prevent any material movement of either with relation to the other, 75 and the transverse bolster 12^a is provided on its front and rear faces with the ribs 16 which prevent any lateral sliding movement of the longitudinal bolsters on the transverse bolster 12^a. 80

The longitudinal bolsters 14 are parallel and are located intermediate the wheels on the central axle 9 and carry the main bolster 17, which latter is cast integral at its ends with the longitudinal bolsters 14 and form 85 an integral part of the latter and also of the transverse bolster 12. The main bolster 17 extends transversely of the truck over the center axle and is provided centrally with the usual center bearing 18. With this construction the weight of the center or main bolster 17 and its load will be sufficient to retain the free ends of the longitudinal bolsters 14 in locking engagement with transverse bolster 12^a, without any securing devices other than the lugs 16. 90

The main or central bolster 17 must be designed especially for heavy loads, and in order to possess the required strength it must have sufficient depth at its central 100 portion. To provide for this necessary depth, without raising the center bearing, and without introducing features which would interfere with the easy removal of the middle axle, I have left the bottom of 105 the bolster open as shown in Fig. 3 so as to permit of the free passage and movement of the middle axle.

The top members of the longitudinal bolsters are as shown in Figs. 1, 3 and 4 pro- 110

vided with flat shelf like projections 19 for the attachment of side bearings, which projections are in a plane above the main bolster and also above the transverse bolster as clearly shown in Fig. 4, thus providing ample means for carrying the side bearing loads and obviating the necessity of using side bearing bridges or carrying members.

10 With the construction as shown, the centers of the longitudinal bolsters are in a plane above the transverse bolster and sufficiently high to carry the side bearings, and the transverse and center bolster are 15 sufficiently low down to provide ample room for the draft gear. Again by making the longitudinal bolster integral with one of the transverse bolsters additional space is provided at one end of the truck which can 20 advantageously be used by the draft gear and draft gear devices, and by making one of the transverse bolsters separate from the other it can be easily removed with its corresponding wheels, thus rendering the middle axle accessible for removal.

It is evident that many slight changes might be resorted to in the relative arrangement of parts shown and described without departing from the spirit and 30 scope of my invention hence I would have it understood that I do not wish to confine myself to the exact construction and arrangement of parts shown and described but,

35 Having fully described my invention what I claim as new and desire to secure by Letters Patent, is:—

1. In a six wheel truck, the combination of a truck frame each side of which is composed of two connected members, two transverse bolsters independent of said side members and supported at their ends thereby, two longitudinal parallel bolsters integral with one of said transverse bolsters and 45 having interlocking connection at their free ends with the other transverse bolster, and a center or main bolster carried by the two longitudinal bolsters.

2. In a six wheel truck, the combination 50 of a truck frame each side of which is composed of two connected members, two transverse bolsters independent of said side members and supported at their free ends by the latter, two longitudinal parallel bolsters

integral with one of said transverse bolsters 55 and each having interlocking engagement at its free end with the other transverse bolster, and a main or center bolster cast integral with the two longitudinal bolsters.

3. As a new article of manufacture, a 60 transverse bolster, two longitudinal parallel bolsters cast integral at one end with said transverse bolster and free at their other ends each free end being provided with means for interlocking it to another trans- 65 verse bolster, and a main or center bolster cast integral with the two longitudinal bolsters.

4. In a six wheel truck, the combination 70 of side frames, two transverse bolsters independent of the side frames and supported at their ends thereby, two longitudinal parallel bolsters cast integral with one of the transverse bolsters and projecting upwardly 75 at the center to provide side bearing supports, each of said longitudinal bolsters being provided at its free end with means for interlocking it with the other transverse bolster, and a main or center bolster integral with the two longitudinal bolsters. 80

5. In a six wheel truck, the combination 85 of two transverse bolsters, two longitudinal bolsters cast integral with one transverse bolster and having hook shaped free ends to engage and be supported on the other transverse bolster, and a main or center bolster cast integral with the two longitudinal bolsters. 95

6. In a six wheel truck, the combination 90 of two transverse bolsters, two longitudinal bolsters cast integral with one of said transverse bolsters and having hook shaped free ends to engage and be supported on the other transverse bolster, the two longitudinal bolsters having upwardly projecting central 95 portions to provide side bearing supports, and a center or main bolster cast integral with the two longitudinal bolsters and located in substantially the same horizontal plane as the transverse bolsters. 100

In testimony whereof, I have signed this specification in the presence of two subscribing witnesses.

JACOB C. LARSEN.
